(57) **CLAIM**

The ornamental design for a jumper clamp, as shown and described.

DESCRIPTION

FIG. 1 is a top perspective view of a jumper clamp showing our new design.

FIG. 2 is a bottom perspective view of the jumper clamp of the present invention.

FIG. 3 is an elevation view of the jumper clamp of the present invention.

FIG. 4 is the opposite elevation view of the jumper clamp of the present invention.

FIG. 5 is a top view of the jumper clamp of the present invention.

FIG. 6 is a bottom view of the jumper clamp of the present invention.

FIG. 7 is a rear view of the jumper clamp of the present invention; and,

FIG. 8 is a front view of the jumper clamp of the present invention.

The broken lines shown represent portions of the jumper clamp that form no part of the claimed design.
